UNITED STATES PATENT OFFICE.

MATEJ KRÁTKÝ, OF HEMINGFORD, NEBRASKA.

DESIGN FOR A FOLLOWER FOR CULINARY VESSELS.

SPECIFICATION forming part of Design No. 23,012, dated January 23, 1894.

Application filed December 4, 1893. Serial No. 492,778. Term of patent 14 years.

To all whom it may concern:

Be it known that I, MATEJ KRÁTKÝ, of Hemingford, in the county of Box Butte and State of Nebraska, have invented a new and original Design for a Follower for Culinary Vessels, of which the following is a full, clear, and exact description.

Reference is to be had to the accompanying drawing forming a part of this specification, in which similar letters of reference indicate corresponding parts in the figure, which represents a perspective view of a follower for culinary vessels embodying my new design.

The leading feature of my design consists in the many sided figure, the sides being bevelled outwardly, and downwardly, as shown. 15

A minor feature consists in the alternate sides *a* having a greater angle than the intervening sides *a'*.

I claim—

The design for a follower for culinary vessels, herein shown and described.

MATEJ KRÁTKÝ.
